TECHNICAL FIELD

The present invention relates to a construction machine having a machine control function.

BACKGROUND ART

In association with responding to information-oriented working, among construction machines such as hydraulic excavators, there are ones having a machine control function that controls the position and posture of work mechanisms such as boom, arm, and bucket in such a manner that the work mechanisms move along a target working surface. As representative one thereof, what limits operation of the work mechanisms in such a manner that the bucket tip does not advance in the direction of the target working surface any more when the bucket tip approaches the target working surface is known.

In standards of civil engineering works execution management, a standard value of the acceptable accuracy in the height direction with respect to the target working surface is defined. When the accuracy of the finished shape of the working surface exceeds the acceptable value, redoing of working occurs and thus the work efficiency lowers. Therefore, the machine control function is required to have the control accuracy necessary to meet the acceptable accuracy of the finished shape.

In association with a spread of the machine control function, development of a function of holding or correcting the bucket angle or the tilt angle with respect to the target working surface is being advanced. Due to this, in the case in which the bucket angle or the tilt angle needs to be held or corrected, the number of hydraulic actuators that need to be simultaneously controlled by the machine control function increases compared with a conventional machine control function that merely carries out combined operation of arm and boom, and it is required to control plural hydraulic actuators simultaneously and accurately.

As one of general methods for improving the control accuracy of the hydraulic actuator, there are methods using feedback control in which the flow rate of inflow to the hydraulic actuator is estimated and the error from a target inflow flow rate is corrected. However, in these control methods, control of the flow rate of inflow to a single hydraulic actuator is assumed in many methods, whereas control of the flow rate of inflow to plural hydraulic actuators through flow dividing is assumed in a small number of methods.

A technique in which flow dividing into plural hydraulic actuators is assumed and a hydraulic pump is electronically controlled on the basis of an estimated inflow flow rate is disclosed in patent document 1. In a control system of a hydraulic excavator shown in patent document 1, at the time of flow dividing control of the hydraulic actuators, the inflow flow rate is controlled by the hydraulic pump regarding a high-load-side hydraulic actuator with a high load and the inflow flow rate is controlled by a pressure compensating valve and a meter-in valve regarding a low-load-side hydraulic actuator with a low load. At this time, the target delivery flow rate of the hydraulic pump is corrected on the basis of the estimated inflow flow rate.

SUMMARY OF THE INVENTION

Problem to be Solved by the Invention

10

The control system of patent document 1 causes the estimation result of the inflow flow rate to be reflected in control of the delivery flow rate of the hydraulic pump. However, the leakage of the inflow flow rate, the influence 15 of flow rate loss due to compression, and characteristics of the meter-in valve differ for each actuator section. Therefore, flow rate errors different for each actuator section are caused. For this reason, it is impossible to correct the flow rate errors of all actuator sections by only correcting the 20 delivery flow rate of the hydraulic pump existing on the most upstream side of the hydraulic circuit. Therefore, for improving the flow rate control accuracy also at the time of flow dividing, the opening amount of the meter-in valve of the hydraulic actuator that operates needs to be directly 25 corrected individually.

In the case of directly correcting the opening amount of the meter-in valve on the basis of the estimated inflow flow rate, interference with the delivery flow rate control of the hydraulic pump needs to be avoided. When both the opening 30 amount of the meter-in valve and the delivery flow rate of the hydraulic pump are corrected on the basis of the estimated inflow flow rate, if the degree of correction is high, there is a possibility that interference of the control of the opening amount and the delivery flow rate occurs and hunting occurs in the inflow flow rate. In contrast, if the degree of correction is low, convergence of the actual inflow flow rate to the hydraulic actuator on the target inflow flow rate is delayed and therefore performance of transient following for the target inflow flow rate lowers.

40 Furthermore, if the delivery flow rate from the hydraulic pump is insufficient with respect to the target inflow flow rate when the opening amount of the meter-in valve is directly corrected on the basis of the estimated inflow flow rate, an error is generated between the target inflow flow rate and the actual inflow flow rate. In this case, the opening amounts of all meter-in valves become larger than the target value and thus distribution control of the inflow flow rate becomes difficult. Therefore, it is desirable to correct only the opening amount of the meter-in valve with avoidance of the situation in which the delivery flow rate from the 45 hydraulic pump is insufficient.

50 The present invention is made in view of the above-described problem and an object thereof is to provide a construction machine that can cause each hydraulic actuator to accurately operate according to operation by an operator in combined operation in which a hydraulic fluid delivered from a hydraulic pump is subjected to flow dividing and is supplied to plural hydraulic actuators.

Means for Solving the Problem

55 In order to achieve the above-described object, the present invention provides a construction machine including a hydraulic pump, a regulator that adjusts the delivery flow rate of the hydraulic pump, a plurality of hydraulic actuators, a plurality of directional control valves that adjust the flow rate of a hydraulic fluid that is delivered from the hydraulic 60

pump and is distributed to the plurality of hydraulic actuators, and an operation device for operating the plurality of hydraulic actuators. The construction machine includes also a controller configured to decide a target flow rate that is a target value of the inflow flow rate of each of the plurality of hydraulic actuators on the basis of an operation signal inputted from the operation device and control the regulator and the plurality of directional control valves according to the respective target flow rates of the plurality of hydraulic actuators. This construction machine includes velocity sensors that sense the respective operation velocities of the plurality of hydraulic actuators. The controller is configured to calculate the respective inflow flow rates of the plurality of hydraulic actuators on the basis of the respective operation velocities of the plurality of hydraulic actuators sensed by the velocity sensors, determine whether or not combined operation in which two or more hydraulic actuators in the plurality of hydraulic actuators are simultaneously operated is being carried out on the basis of the operation signal inputted from the operation device, and in a case of determining that the combined operation is being carried out, control the regulator in such a manner that the delivery flow rate of the hydraulic pump becomes larger than the total target flow rate of the plurality of hydraulic actuators and control the respective opening amounts of the plurality of directional control valves in such a manner that the difference between the respective target flow rates of the plurality of hydraulic actuators and the respective inflow flow rates of the plurality of hydraulic actuators sensed by the velocity sensors becomes small.

According to the present invention configured as above, when it is determined that the combined operation is being carried out, the delivery flow rate of the hydraulic pump is increased relative to the total target flow rate of the plural hydraulic actuators. In addition, the difference between the respective inflow flow rates and the respective target flow rates of the plural hydraulic actuators is reflected only in control of the respective opening amounts of the plural directional control valves. This can prevent interference between the delivery flow rate control of the hydraulic pump and the opening control of the plural directional control valves with avoidance of the situation in which the delivery flow rate of the hydraulic pump is insufficient. Due to this, the flow rate can be accurately distributed to the plural hydraulic actuators. Therefore, it becomes possible to cause the plural hydraulic actuators to accurately operate according to operation by the operator.

Advantages of the Invention

According to the construction machine according to the present invention, it becomes possible to cause each hydraulic actuator to accurately operate according to operation by an operator in combined operation in which a hydraulic fluid of a hydraulic pump is subjected to flow dividing and is supplied to plural hydraulic actuators.

BRIEF DESCRIPTION OF THE DRAWINGS

FIG. 1 is a diagram schematically illustrating the appearance of a hydraulic excavator according to a first embodiment of the present invention.

FIG. 2 is a diagram schematically illustrating a hydraulic actuator control system mounted in the hydraulic excavator illustrated in FIG. 1.

FIG. 3 is a functional block diagram that represents details of processing functions of a controller illustrated in FIG. 2.

FIG. 4 is a control block diagram that represents details of a calculation function of a pump delivery flow rate control section illustrated in FIG. 3 and a calculation function of a bleed-off opening control section.

5 FIG. 5 is a diagram illustrating one example of calculation results in a target flow rate deciding section, a combined operation determining section, and the pump delivery flow rate control section that are illustrated in FIG. 3.

10 FIG. 6 is a diagram illustrating an effect of correction of the error between the target flow rate and the estimated flow rate to the hydraulic actuator according to the first embodiment of the present invention.

15 FIG. 7 is a functional block diagram that represents details of processing functions of the controller according to a second embodiment of the present invention.

FIG. 8 is a control block diagram that represents details of a calculation function of the bleed-off opening control section according to the second embodiment of the present invention.

20 FIG. 9 is a diagram illustrating change in the flow rate of discharge from a bleed-off valve to a tank according to the second embodiment of the present invention.

FIG. 10 is a diagram schematically illustrating a hydraulic actuator control system according to a third embodiment of the present invention.

25 FIG. 11 is a functional block diagram that represents details of processing functions of the controller according to the third embodiment of the present invention.

FIG. 12 is a diagram schematically illustrating a hydraulic actuator control system according to a fourth embodiment of the present invention.

30 FIG. 13 is a functional block diagram that represents details of processing functions of the controller according to the fourth embodiment of the present invention.

35 FIG. 14 is a control block diagram that represents details of a calculation function of the bleed-off opening control section according to a fifth embodiment of the present invention.

40 FIG. 15 is a diagram schematically illustrating a hydraulic actuator control system according to a sixth embodiment of the present invention.

MODES FOR CARRYING OUT THE INVENTION

45 Description will be made below with reference to the drawings by taking a hydraulic excavator as an example as a construction machine according to embodiments of the present invention. In the respective diagrams, equivalent components are given the same numeral and overlapping description is omitted as appropriate.

First Embodiment

55 FIG. 1 is a diagram schematically illustrating the appearance of a hydraulic excavator according to a first embodiment of the present invention.

In FIG. 1, a hydraulic excavator 100 includes an articulated front device (front work implement) 1 configured by linking plural driven members (boom 4, arm 5, and bucket (work equipment) 6) that are each pivoted in the perpendicular direction, and an upper swing structure 2 and a lower track structure 3 that configure a machine body. The upper swing structure 2 is disposed swingably relative to the lower track structure 3. Furthermore, the base end of the boom 4 of the front device 1 is supported by the front part of the upper swing structure 2 pivotally in the perpendicular direc-

tion. One end of the arm 5 is supported by the end part (tip) of the boom 4 different from the base end pivotally in the perpendicular direction. The bucket 6 is supported by the other end of the arm 5 pivotally in the perpendicular direction. The boom 4, the arm 5, the bucket 6, the upper swing structure 2, and the lower track structure 3 are driven by a boom cylinder 4a, an arm cylinder 5a, a bucket cylinder 6a, a swing motor 2a, and left and right traveling motors 3a (only one traveling motor is illustrated), respectively, that are hydraulic actuators.

The boom 4, the arm 5, and the bucket 6 operate on a single plane (hereinafter, operation plane). The operation plane is a plane orthogonal to the pivot axes of the boom 4, the arm 5, and the bucket 6 and can be set to pass through the center of the boom 4, the arm 5, and the bucket 6 in the width direction.

In a cab 9 in which an operator rides, an operation lever device (operation device) 9a that outputs an operation signal for operating the hydraulic actuators 2a and 4a to 6a and an operation lever device (operation device) 9b that outputs an operation signal for driving the traveling motors 3a are disposed. The operation lever device 9a is two operation levers that can be inclined forward, rearward, leftward, and rightward and the operation lever device 9b is two operation levers that can be inclined in the front-rear direction. The operation lever devices 9a and 9b include a sensor that electrically senses an operation signal corresponding to the inclination amount of the operation lever (lever operation amount). The lever operation amount sensed by this sensor is outputted to a controller 10 (illustrated in FIG. 2) that is a controller through an electrical wiring line.

Operation control of the boom cylinder 4a, the arm cylinder 5a, the bucket cylinder 6a, the swing motor 2a, and the left and right traveling motors 3a is carried out by controlling, by a control valve 8, the direction and the flow rate of a hydraulic operating fluid supplied from a hydraulic pump 7 driven by a prime mover 40 to the respective hydraulic actuators 2a to 6a. Control of the control valve 8 is carried out by a drive signal (pilot pressure) output from a pilot pump 70 to be described later through a solenoid proportional pressure reducing valve to be described later. By controlling the solenoid proportional pressure reducing valve by the controller 10 on the basis of the operation signal from the operation lever devices 9a and 9b, operation of the respective hydraulic actuators 2a to 6a is controlled.

The operation lever devices 9a and 9b may be a hydraulic pilot system different from the above description and may be each configured to supply a pilot pressure according to the operation direction and the operation amount of the operation lever operated by an operator to the control valve 8 as a drive signal. In this case, the configuration may be made in such a manner that the pilot pressure according to the operation amount is sensed by a pressure sensor and the sensed pressure is outputted to the controller 10 as an electrical signal and the respective hydraulic actuators 2a to 6a are driven by the solenoid proportional pressure reducing valve to be described later.

Inertial measurement units 12 to 14 are what measure the angular velocity and the acceleration. The boom inertial measurement unit 12, the arm inertial measurement unit 13, and the bucket inertial measurement unit 14 configure a boom cylinder velocity sensor 12, an arm cylinder velocity sensor 13, and a bucket cylinder velocity sensor 14 that sense the operation velocity of the boom cylinder 4a, the arm cylinder 5a, and the bucket cylinder 6a, respectively, on the basis of the measured angular velocity and acceleration.

The cylinder velocity sensor is not limited to the inertial measurement unit. For example, the configuration may be made in such a manner that a stroke sensor is disposed for each the boom cylinder 4a, the arm cylinder 5a, and the bucket cylinder 6a and the operation velocity of the boom cylinder 4a, the arm cylinder 5a, and the bucket cylinder 6a is computed by carrying out numerical differentiation of the stroke change amount.

FIG. 2 is a diagram schematically illustrating a hydraulic actuator control system mounted in the hydraulic excavator 100. For simplification of explanation, only elements necessary for explanation of the invention are depicted. To simplify explanation, in FIG. 2, only a pump section to which the boom 4, the arm 5, and the bucket 6 are connected is depicted to be described.

The hydraulic actuator control system is composed of the control valve 8 that drives the respective hydraulic actuators 2a to 6a, the hydraulic pump 7 that supplies the hydraulic fluid to the control valve 8, the pilot pump 70 that supplies the pilot pressure that becomes the drive signal of the control valve 8, and the prime mover 40 for driving the hydraulic pump 7. In the present embodiment, a variable displacement type is employed as the hydraulic pump 7, and a solenoid proportional pressure reducing valve 7a for the variable displacement pump operates on the basis of a current command from the controller 10 and thereby the capacity of the hydraulic pump 7 is adjusted and the delivery flow rate of the hydraulic pump 7 is controlled. A configuration may be employed in which a fixed displacement type is employed as the hydraulic pump 7 and the rotation velocity of the prime mover 40 is adjusted by a control command from the controller 10 to control the delivery flow rate of the hydraulic pump 7.

The hydraulic fluid delivered by the hydraulic pump 7 is distributed to the respective hydraulic actuators by a boom directional control valve 8a1, an arm directional control valve 8a3, and a bucket directional control valve 8a5. The boom directional control valve 8a1 serves as an opening (meter-in opening) through which one of a bottom-side fluid chamber 4a1 or a rod-side fluid chamber 4a2 of the boom cylinder 4a communicates with a hydraulic fluid line that leads to the hydraulic pump 7, and serves as an opening (meter-out opening) through which the other communicates with a hydraulic fluid line that leads to a tank 41. Solenoid proportional pressure reducing valves 8a2 for the boom directional control valve operate on the basis of the current command ordered from the controller 10 and thereby the pilot pressure is adjusted, and thus the opening amount when the boom directional control valve 8a1 communicates with the bottom-side fluid chamber 4a1 or the rod-side fluid chamber 4a2 is controlled. When the solenoid proportional pressure reducing valve 8a2a is driven, the hydraulic fluid flows from the bottom-side fluid chamber 4a1 to the rod-side fluid chamber 4a2. On the other hand, when the solenoid proportional pressure reducing valve 8a2b is driven, the hydraulic fluid flows from the rod-side fluid chamber 4a2 to the bottom-side fluid chamber 4a1. The arm directional control valve 8a3 also similarly communicates with a bottom-side fluid chamber 5a1 and a rod-side fluid chamber 5a2 of the arm cylinder 5a and the opening amount thereof is controlled by solenoid proportional pressure reducing valves 8a4 for the arm directional control valve. The bucket directional control valve 8a5 communicates with a bottom-side fluid chamber 6a1 and a rod-side fluid chamber 6a2 of the bucket cylinder 6a and the opening amount thereof is controlled by solenoid proportional pressure reducing valves 8a6 for the bucket directional control valve.

Part of the hydraulic fluid delivered from the hydraulic pump 7 is discharged to the tank 41 by a bleed-off valve 8b1 communicating a hydraulic fluid line to the tank 41. For the bleed-off valve 8b1, a solenoid proportional pressure reducing valve 8b2 for the bleed-off valve operates on the basis of the current command ordered from the controller 10 and thereby the pilot pressure is adjusted, and thus the flow rate of the discharge to the tank 41 is controlled. Instead of installing the bleed-off valve 8b1, a configuration may be employed in which directional control valves of an open center type that allow three-direction control are employed as the directional control valves 8a1, 8a3, and 8a5 and a bleed-off opening is adjusted in conjunction with the meter-in opening and the meter-out opening.

FIG. 3 is a functional block diagram that represents details of processing functions of the controller 10. In FIG. 3, description will be made with omission of functions that do not directly relate to the present invention similarly to FIG. 2.

In FIG. 3, the controller 10 has a target flow rate deciding section 10a, a combined operation determining section 10b, a pump delivery flow rate control section 10c, a boom cylinder flow rate estimating section 10d1, an arm cylinder flow rate estimating section 10d2, a bucket cylinder flow rate estimating section 10d3, a boom cylinder meter-in opening control section 10e1, an arm cylinder meter-in opening control section 10e2, a bucket cylinder meter-in opening control section 10e3, and a bleed-off opening control section 10f.

The target flow rate deciding section 10a decides target flow rates Q_{a1} , Q_{a2} , and Q_{a3} of inflow to the respective hydraulic actuators and the target flow rates of the respective hydraulic actuators 4a to 6a are outputted to the boom cylinder meter-in opening control section 10e1, the arm cylinder meter-in opening control section 10e2, and the bucket cylinder meter-in opening control section 10e3.

In the present embodiment, the target flow rates Q_{a1} , Q_{a2} , and Q_{a3} of inflow to the respective hydraulic actuators 4a to 6a are decided on the basis of the operation amount inputted from the operation lever device 9a. A configuration may be employed in which the target flow rates Q_{a1} , Q_{a2} , and Q_{a3} are decided on the basis of the posture of the front device 1 of the hydraulic excavator 100 or the relative positional relation between the work equipment 6 of the front device 1 and the target working surface besides the operation amount inputted from the operation lever device 9a.

The combined operation determining section 10b determines whether the present state is the state in which two or more hydraulic actuators are simultaneously operating, i.e. a combined operation state. A determination flag that is a binary signal indicating whether the present state is the combined operation state is outputted to the pump delivery flow rate control section 10c.

In the present embodiment, whether the present state is the combined operation state is determined on the basis of the target flow rates Q_{a1} , Q_{a2} , and Q_{a3} inputted from the target flow rate deciding section 10a. Whether the present state is the combined operation state may be determined on the basis of the operation amount inputted from the operation lever device 9a.

The pump delivery flow rate control section 10c decides the target delivery flow rate of the hydraulic pump 7 on the basis of a total value Q_p of the target flow rates to the respective hydraulic actuators 4a to 6a computed by the target flow rate deciding section 10a and the combined operation determination flag inputted from the combined operation determining section 10b. When it is determined

that the combined operation is being carried out, a flow rate obtained by adding an offset flow rate to be described later with FIG. 4 to the total value Q_p of the target flow rates is set as the target delivery flow rate of the hydraulic pump 7 and a current command $I_{p,ref}$ for adjustment to capacity corresponding to it is outputted to the solenoid proportional pressure reducing valve 7a for the variable displacement pump.

The boom cylinder flow rate estimating section 10d1, the arm cylinder flow rate estimating section 10d2, and the bucket cylinder flow rate estimating section 10d3 compute estimated flow rates Q_{e1} , Q_{e2} , and Q_{e3} at which inflow to the boom cylinder 4a, the arm cylinder 5a, and the bucket cylinder 6a is estimated to be caused, on the basis of cylinder velocities V_{e1} , V_{e2} , and V_{e3} sensed by the boom cylinder velocity sensor 12, the arm cylinder velocity sensor 13, and the bucket cylinder velocity sensor 14. In the boom cylinder flow rate estimating section 10d1, the estimated flow rate Q_{e1} of the boom cylinder 4a is computed from the following expression (1).

[Expression 1]

$$Q_{e1} = S_{a1} V_{e1} \quad (1)$$

Here, S_{a1} is the sectional area of the boom cylinder 4a. When the hydraulic fluid flows in from the bottom-side fluid chamber 4a1, the sectional area of the bottom side of the boom cylinder 4a is defined as S_{a1} . When the hydraulic fluid flows in from the rod-side fluid chamber 4a2, the sectional area of the rod side of the boom cylinder 4a is defined as S_{a1} . Also regarding the arm cylinder flow rate estimating section 10d2 and the bucket cylinder flow rate estimating section 10d3, the estimated flow rates Q_{e2} and Q_{e3} are computed by similar calculation with use of expression (1). Thus, detailed description is omitted. The estimated flow rates Q_{e1} , Q_{e2} , and Q_{e3} are outputted to the boom cylinder meter-in opening control section 10e1, the arm cylinder meter-in opening control section 10e2, and the bucket cylinder meter-in opening control section 10e3, respectively.

The boom cylinder meter-in opening control section 10e1, the arm cylinder meter-in opening control section 10e2, and the bucket cylinder meter-in opening control section 10e3 decide the opening amount of the meter-in valves 8a1, 8a3, and 8a5 in such a manner as to correct the error between the target flow rate and the estimated flow rate, on the basis of the inflow flow rate Q_{e1} to the boom cylinder estimated by the boom cylinder flow rate estimating section 10d1, the inflow flow rate Q_{e2} to the arm cylinder estimated by the arm cylinder flow rate estimating section 10d2, the inflow flow rate Q_{e3} to the bucket cylinder estimated by the bucket cylinder flow rate estimating section 10d3, and the target flow rates Q_{a1} , Q_{a2} , and Q_{a3} to the respective hydraulic actuators computed by the target flow rate deciding section 10a. Current commands $I_{a1,ref}$, $I_{a2,ref}$, and $I_{a3,ref}$ for adjustment to the decided opening amounts are outputted to the solenoid proportional pressure reducing valves 8a2 for the boom directional control valve, the solenoid proportional pressure reducing valves 8a4 for the arm directional control valve, and the solenoid proportional pressure reducing valves 8a6 for the bucket directional control valve.

In the boom cylinder meter-in opening control section 10e1, the current command $T_{a1,ref}$ to the solenoid proportional pressure reducing valves 8a2 for the boom directional control valve is calculated with the following expressions (2), (3), and (4).

[Expression 2]

$$Q_{a1,new} = Q_{a1} + K_f \int (Q_{a1} - Q_{e1}) dt \quad (2)$$

[Expression 3]

$$A_{a1} = f_1(Q_{a1,new}) \quad (3)$$

[Expression 4]

$$I_{a1,ref} = g_1(A_{a1}) \quad (4)$$

Here, $Q_{a1,new}$ is the target flow rate to the boom cylinder $4a$ resulting from addition of a correction amount computed on the basis of the estimated flow rate Q_{e1} . A_{a1} is the target opening amount of the boom meter-in valve $8a1$. K_f is the feedback gain of integral control. f_1 is a transformation table from the post-correction target flow rate $Q_{a1,new}$ to the target opening amount A_{a1} . g_1 is a transformation table from the target opening amount A_{a1} to the current command $I_{a1,ref}$. In expression (2), a feed-forward amount to command the target flow rate Q_{a1} as it is and a feedback amount to correct the error between the target flow rate Q_{a1} and the estimated flow rate Q_{e1} are added to each other. By correcting the error between the target flow rate Q_{a1} and the estimated flow rate Q_{e1} , achievement of robustness against variation in dynamic characteristics of the hydraulic system due to the influence of the fluid temperature and so forth is intended. Furthermore, by integrating the error between the target flow rate Q_{a1} and the estimated flow rate Q_{e1} to make the correction amount, a stationary flow rate error that occurs due to an error in the flow rate coefficient and flow rate loss of the hydraulic fluid is eliminated.

Also in the arm cylinder meter-in opening control section $10e2$ and the bucket cylinder meter-in opening control section $10e3$, the current commands $I_{a2,ref}$ and $I_{a3,ref}$ are computed by similar calculation with use of expressions (2) to (4). Thus, detailed description is omitted.

The bleed-off opening control section $10f$ calculates and outputs a current command $I_{b,ref}$ to the solenoid proportional pressure reducing valve $8b2$ for bleed-off. As one example, the bleed-off valve $8b1$ in the present embodiment is controlled to be always in the state in which a constant opening is opened irrespective of the operation amount of the operation levers $9a$ and $9b$. A configuration may be employed in which the opening amount of the bleed-off valve $8b1$ is adjusted to be subordinate to the opening amount of the directional control valves $8a1$, $8a3$, and $8a5$.

FIG. 4 is a control block diagram that represents details of a calculation function of the pump delivery flow rate control section $10c$ and a calculation function of the bleed-off opening control section $10f$.

In the pump delivery flow rate control section $10c$, on the basis of the determination flag inputted from the combined operation determining section $10b$, a constant flow rate Q_{const} is selected by a selector SLT1 when the combined operation is being carried out and a zero flow rate $Q_0=0$ is selected by the selector SLT1 when the combined operation is not being carried out. The selected flow rate is transmitted as an offset command Q_{offset} and is added to a target flow rate Q_p to become a post-correction target flow rate $Q_{p,new}$. Finally, transformation is carried out from the post-correction target flow rate $Q_{p,new}$ to the current command $I_{p,ref}$ by a transformation table TBL and the current command $I_{p,ref}$ is outputted to the solenoid proportional pressure reducing valve $7a$ for the variable displacement pump.

By determining that the combined operation is being carried out and increasing the delivery flow rate of the

hydraulic pump 7 with respect to the target flow rate Q_p , the situation in which the delivery flow rate of the hydraulic pump 7 is insufficient with respect to the target flow rate Q_p can be surely avoided.

5 In the bleed-off opening control section $10f$, a constant opening amount A_{const} set in advance is given as a target opening amount A_b and transformation is carried out from the target opening amount A_b to the current command $I_{b,ref}$ by a transformation table TBL2. The current command $I_{b,ref}$ is outputted to the solenoid proportional pressure reducing valve $8b2$ for bleed-off.

By always opening the bleed-off valve $8b1$ by the constant opening amount A_{const} , the delivery flow rate of the hydraulic pump 7 as the part that becomes surplus due to the offset command Q_{offset} can be discharged from the bleed-off valve $8b1$ and the situation in which the surplus hydraulic fluid flows in to the hydraulic actuators $4a$ to $6a$ can be avoided.

FIG. 5 is a diagram illustrating one example of calculation results in the target flow rate deciding section $10a$, the 15 combined operation determining section $10b$, and the pump delivery flow rate control section $10c$.

FIG. 5(a) illustrates the target flow rate decided by the target flow rate deciding section $10a$ based on the operation amount inputted from the operation lever device $9a$. In the 25 present embodiment, the case in which first the target flow rate Q_{a1} is input to the boom cylinder meter-in opening control section $10e1$ and the target flow rate Q_{a2} is input to the arm cylinder meter-in opening control section $10e2$ at a clock time t_1 is taken as one example. In this case, at and 30 after the clock time t_1 , the target flow rates Q_{a1} and Q_{a2} are simultaneously output from the target flow rate deciding section $10a$.

FIG. 5(b) illustrates the determination flag judged by the 35 combined operation determining section $10b$ based on the target flow rate inputted from the target flow rate deciding section $10a$. Before the clock time t_1 , since being given only the target flow rate Q_{a1} to the boom cylinder $4a$ from the target flow rate deciding section $10a$, the combined operation determining section $10b$ judges that the combined operation is not being carried out, and outputs the determination flag as False. At and after the clock time t_1 , since being given the target flow rate Q_{a1} to the boom cylinder $4a$ and the target flow rate Q_{a2} to the arm cylinder $5a$ from the target flow rate deciding section $10a$, the combined operation determining section $10b$ judges that the combined operation is being carried out, and outputs the determination flag as True.

FIG. 5(c) illustrates the post-correction target flow rate $Q_{p,new}$ decided by the pump delivery flow rate control section $10d$ based on the target flow rate inputted from the target flow rate deciding section $10a$ and the determination flag inputted from the combined operation determining section $10b$. Before the clock time t_1 , the target flow rate deciding section $10a$ outputs only the target flow rate Q_{a1} and the combined operation determining section $10b$ determines that the combined operation is not being carried out. Therefore, post-correction target flow rate $Q_{p,new}=Q_{a1}$ holds. At and after the clock time t_1 , the target flow rate deciding section $10a$ outputs the target flow rates Q_{a1} and Q_{a2} and the combined operation determining section $10b$ determines that the combined operation is being carried out. Therefore, post-correction target flow rate $Q_{p,new}=Q_{a1}+Q_{a2}+Q_{offset}$ holds.

FIG. 6 is a diagram illustrating an effect of correction of 65 the error between the target flow rate and the estimated flow rate to the hydraulic actuator according to the present embodiment. Similarly to FIG. 5, the case in which the target

flow rate Q_{a1} is input to the boom cylinder meter-in opening control section **10e1** and the target flow rate Q_{a2} is input to the arm cylinder meter-in opening control section **10e2** is taken as one example.

In FIG. 6(a), as a comparative example of the present embodiment, one example of flow rate distribution of the respective hydraulic actuators in the case in which only the target delivery flow rate of the hydraulic pump 7 is corrected and the meter-in opening is not corrected is illustrated. Flow rate losses generated in the boom cylinder **4a** and the arm cylinder **5a** and characteristics and flow rate coefficients of the boom meter-in valve **8a1** and the arm meter-in valve **8a3** are different. Therefore, an error is yielded in the distribution ratio of the inflow flow rates to the boom cylinder **4a** and the arm cylinder **5a** and stationary errors are generated between the target flow rate Q_{a1} and the estimated flow rate Q_{e1} and between the target flow rate Q_{a2} and the estimated flow rate Q_{e2} .

In FIG. 6(b), one example of flow rate distribution of the respective hydraulic actuators according to the present embodiment is illustrated. According to the errors between the target flow rate Q_{a1} and the estimated flow rate Q_{e1} and between the target flow rate Q_{a2} and the estimated flow rate Q_{e2} , the boom cylinder meter-in opening control section **10e1** and the arm cylinder meter-in opening control section **10e2** correct the target opening amount on the basis of expressions (2) to (4). Due to this, the error in the distribution ratio of the inflow flow rates to the boom cylinder **4a** and the arm cylinder **5a** is corrected and the stationary errors between the target flow rate Q_{a1} and the estimated flow rate Q_{e1} and between the target flow rate Q_{a2} and the estimated flow rate Q_{e2} are dissolved. Furthermore, after the clock time t_1 , at which the combined operation state is made, the performance of following of the arm estimated flow rate Q_{e2} for the target flow rate Q_{a2} is improved due to the increase in the delivery flow rate of the hydraulic pump 7 by the pump delivery flow rate control section **10c**.

In the present embodiment, the construction machine **100** includes the hydraulic pump 7, the regulator **7a** that adjusts the delivery flow rate of the hydraulic pump 7, the plural hydraulic actuators **4a**, **5a**, and **6a**, the plural directional control valves **8a1**, **8a3**, and **8a5** that adjust the flow rate of the hydraulic fluid that is delivered from the hydraulic pump 7 and is distributed to the plural hydraulic actuators **4a**, **5a**, and **6a**, and the operation device **9a** for operating the plural hydraulic actuators **4a**, **5a**, and **6a**. The construction machine **100** includes also the controller **10** that decides the target flow rate that is the target value of the inflow flow rate of each of the plural hydraulic actuators **4a**, **5a**, and **6a** on the basis of an operation signal inputted from the operation device **9a** and controls the regulator **7a** and the plural directional control valves **8a1**, **8a3**, and **8a5** according to the respective target flow rates of the plural hydraulic actuators **4a**, **5a**, and **6a**. This construction machine **100** includes the velocity sensors **12** to **14** that sense the respective operation velocities of the plural hydraulic actuators **4a**, **5a**, and **6a**. The controller **10** calculates the respective inflow flow rates of the plural hydraulic actuators **4a**, **5a**, and **6a** on the basis of the respective operation velocities of the plural hydraulic actuators **4a**, **5a**, and **6a** sensed by the velocity sensors **12** to **14**. The controller **10** determines whether or not the combined operation in which two or more hydraulic actuators in the plural hydraulic actuators **4a**, **5a**, and **6a** are simultaneously operated is being carried out on the basis of the operation signal inputted from the operation device **9a**. When determining that the combined operation is being carried out, the controller **10** controls the regulator **7a** in

such a manner that the delivery flow rate of the hydraulic pump 7 becomes larger than the total target flow rate of the plural hydraulic actuators and controls the respective opening amounts of the plural directional control valves **8a1**, **8a3**, and **8a5** in such a manner that the difference between the respective target flow rates of the plural hydraulic actuators **4a**, **5a**, and **6a** and the respective inflow flow rates of the plural hydraulic actuators **4a**, **5a**, and **6a** sensed by the velocity sensors **12** to **14** becomes small.

According to the present embodiment configured as above, when it is determined that the combined operation is being carried out, the delivery flow rate of the hydraulic pump 7 is increased relative to the total target flow rate of the plural hydraulic actuators **4a**, **5a**, and **6a**. In addition, the difference between the respective inflow flow rates and the respective target flow rates of the plural hydraulic actuators **4a**, **5a**, and **6a** is reflected only in control of the respective opening amounts of the plural directional control valves **8a1**, **8a3**, and **8a5**. This can prevent interference between the delivery flow rate control of the hydraulic pump 7 and the opening control of the plural directional control valves **8a1**, **8a3**, and **8a5** with avoidance of the situation in which the delivery flow rate of the hydraulic pump 7 is insufficient. Due to this, the flow rate can be accurately distributed to the plural hydraulic actuators **4a**, **5a**, and **6a**. Therefore, it becomes possible to cause the plural hydraulic actuators **4a**, **5a**, and **6a** to accurately operate according to operation by the operator.

Second Embodiment

A hydraulic excavator according to a second embodiment of the present invention will be described with focus on a difference from the first embodiment.

FIG. 7 is a functional block diagram that represents details of processing functions of the controller **10** according to the second embodiment.

In the present embodiment, the bleed-off valve **8b1** is driven independently of the directional control valves **8a1**, **8a3**, and **8a5**. The bleed-off opening control section **10f** illustrated in FIG. 7 decides the opening amount of the bleed-off valve **8b1** on the basis of the combined operation determination flag inputted from the combined operation determining section **10b**. When it is determined that the combined operation is being carried out, a command to open the bleed-off valve **8b1** is generated and the current command $I_{b,ref}$ is outputted to the solenoid proportional pressure reducing valve **8b2** for the bleed-off valve. When it is determined that the combined operation is not being carried out, a command to fully close the bleed-off valve **8b1** is generated and the current command $I_{b,ref}$ is outputted to the solenoid proportional pressure reducing valve **8b2** for the bleed-off valve.

FIG. 8 is a control block diagram that represents details of a calculation function of the bleed-off opening control section **10f** according to the second embodiment.

In the bleed-off opening control section **10f**, on the basis of the determination flag inputted from the combined operation determining section **10b**, the constant opening A_{const} is selected by a selector **SLT2** when the combined operation is being carried out and zero opening $A_0=0$ is selected by the selector **SLT2** when the combined operation is not being carried out. The selected opening amount is transmitted as the target opening A_b of the bleed-off valve **8b1** and transformation is carried out from the target opening A_b to the current command $I_{b,ref}$ by the transformation table **TBL2**.

13

The current command $I_{b,ref}$ is outputted to the solenoid proportional pressure reducing valve **8b2** for the bleed-off valve.

FIG. 9 is a diagram illustrating change in the flow rate of discharge from the bleed-off valve **8b1** to the tank **41** according to the second embodiment.

FIG. 9(a) illustrates the target flow rate decided by the target flow rate deciding section **10a** based on the operation amount inputted from the operation lever device **9a**. Similarly to FIG. 5(a), the case in which first the target flow rate Q_{a1} is input to the boom cylinder meter-in opening control section **10e1** and the target flow rate Q_{a2} is input to the arm cylinder meter-in opening control section **10e2** at the clock time t_1 is taken as one example.

FIG. 9(b) illustrates the target opening A_b of the bleed-off valve **8b1** decided by the bleed-off opening control section **10f** based on the determination flag inputted from the combined operation determining section **10b**. Before the clock time t_1 , the combined operation determining section **10b** determines that the combined operation is not being carried out. Therefore, target opening $A_b=0$ holds and the setting is made in such a manner that the bleed-off valve **8b1** is fully closed. At and after the clock time t_1 , the combined operation determining section **10b** determines that the combined operation is being carried out, and therefore target opening $A_b=A_{const}$ holds.

FIG. 9(c) illustrates a bleed-off discharge flow rate Q_b at which discharge is carried out from the bleed-off valve **8b1** to the tank **41** when the current command $I_{b,ref}$ is input to the solenoid proportional pressure reducing valve **8b2** for the bleed-off valve from the bleed-off opening control section **10f** and the bleed-off valve **8b1** is driven. Before the clock time t_1 , the bleed-off valve **8b1** is in the fully-closed state and bleed-off discharge flow rate $Q_b=0$ holds. At and after the clock time t_1 , the state in which the opening of the bleed-off valve **8b1** is opened by A_{const} is made, and the bleed-off discharge flow rate Q_b according to the delivery pressure of the hydraulic pump **7** is discharged to the tank **41**.

The construction machine **100** according to the present embodiment includes the bleed-off valve **8b1** for discharging the surplus part of the hydraulic fluid delivered by the hydraulic pump **7** in such a manner that the bleed-off valve **8b1** is driven independently of the plural directional control valves **8a1**, **8a3**, and **8a5**. The controller **10** carries out control to open the bleed-off valve **8b1** when determining that the combined operation is being carried out and close the bleed-off valve **8b1** when determining that the combined operation is not being carried out.

According to the present embodiment configured as above, the following effect is obtained in addition to the same effects as the first embodiment.

By fully closing the bleed-off valve **8b1** when the combined operation is not being carried out, wasteful flow rate discharge from the bleed-off valve **8b1** to the tank **41** can be suppressed while the flow rate error at the time of the combined operation is corrected by the boom cylinder meter-in opening control section **10e1**, the arm cylinder meter-in opening control section **10e2**, and the bucket cylinder meter-in opening control section **10e3**. This makes it possible to achieve both the control accuracy of the hydraulic actuator and the energy saving performance.

Third Embodiment

A hydraulic excavator according to a third embodiment of the present invention will be described with focus on a difference from the first embodiment.

14

FIG. 10 is a diagram schematically illustrating a hydraulic actuator control system according to the third embodiment.

In the hydraulic actuator control system illustrated in FIG. 10, a boom cylinder flow rate sensor **71** is installed upstream of the boom directional control valve **8a1**, and an arm cylinder flow rate sensor **72** is installed upstream of the arm directional control valve **8a3**, and a bucket cylinder flow rate sensor **73** is installed upstream of the bucket directional control valve **8a5**. The flow rates of inflow to the boom cylinder **4a**, the arm cylinder **5a**, and the bucket cylinder **6a** are directly estimated by the flow rate sensors **71** to **73**. The flow rate sensors **71** to **73** are connected to the controller **10** through electrical wiring lines and output a flow rate sensing result to the controller **10**.

FIG. 11 is a functional block diagram that represents details of processing functions of the controller **10** according to the third embodiment.

The boom cylinder flow rate sensor **71**, the arm cylinder flow rate sensor **72**, and the bucket cylinder flow rate sensor **73** output the computed estimated flow rates Q_{e1} , Q_{e2} , and Q_{e3} to the boom cylinder meter-in opening control section **10e1**, the arm cylinder meter-in opening control section **10e2**, and the bucket cylinder meter-in opening control section **10e3**.

The construction machine **100** according to the present embodiment includes the plural flow rate sensors **71** to **73** each disposed upstream of the plural directional control valves **8a1**, **8a3**, and **8a5** instead of the velocity sensors **12** to **14**.

According to the present embodiment configured as above, the following effect is obtained in addition to the same effects as the first embodiment.

By directly sensing the inflow flow rates to the respective hydraulic actuators **4a** to **6a** by the boom cylinder flow rate sensor **71**, the arm cylinder flow rate sensor **72**, and the bucket cylinder flow rate sensor **73**, the estimation error of the estimated flow rates Q_{e1} , Q_{e2} , and Q_{e3} due to the influence of friction and vibration at the time of hydraulic actuator operation can be removed and the estimated flow rates Q_{e1} , Q_{e2} , and Q_{e3} can be computed more accurately. In addition, by controlling each opening amount of the directional control valves **8a1**, **8a3**, and **8a5** by using the more accurate estimated flow rates Q_{e1} , Q_{e2} , and Q_{e3} , the inflow flow rates to the hydraulic actuators **4a**, **5a**, and **6a** can be distributed more accurately.

Fourth Embodiment

50 A hydraulic excavator according to a fourth embodiment of the present invention will be described with focus on a difference from the first embodiment.

FIG. 12 is a diagram schematically illustrating a hydraulic actuator control system according to the fourth embodiment.

55 In the hydraulic actuator control system illustrated in FIG. 12, a pump delivery pressure sensor **51** for measuring the delivery pressure of the hydraulic pump **7**, boom load pressure sensors **52** and **55** for measuring the boom load pressure on the downstream side of the boom meter-in valve **8a1**, arm load pressure sensors **53** and **56** for measuring the arm load pressure on the downstream side of the arm meter-in valve **8a3**, and bucket load pressure sensors **54** and **57** for measuring the bucket load pressure on the downstream side of the bucket meter-in valve **8a5** are installed. The pressure sensors **51** to **57** are connected to the controller **10** through electrical wiring lines and output a pressure sensing result to the controller **10**.

FIG. 13 is a functional block diagram that represents details of processing functions of the controller 10 according to the fourth embodiment.

To the boom cylinder meter-in opening control section 10e1, a pump delivery pressure P_d sensed by the pump delivery pressure sensor 51 and a boom load pressure P_{a1} sensed by the boom load pressure sensors 52 and 55 are input in addition to the target flow rate Q_{a1} computed by the target flow rate deciding section 10a and the estimated flow rate Q_{e1} estimated by a boom cylinder flow rate estimating section 10/1. The boom cylinder meter-in opening control section 10e1 transforms, by the following expression (5), the post-correction target flow rate $Q_{a1,new}$ computed by expression (2) to the target opening amount A_{a1} .

[Expression 5]

$$A_{a1} = k \frac{Q_{a1,new}}{\sqrt{P_d - P_{a1}}} \quad (5)$$

Here, k is a positive constant value defined with the influence of the flow rate coefficient, the density of the hydraulic fluid, and so forth being also taken into consideration. As shown in the denominator of the right side of expression (5), the target opening amount A_{a1} of the boom meter-in valve 8a1 is decided in consideration of the differential pressure between the pressure on the upstream side of the boom meter-in valve 8a1 (pump delivery pressure P_d) and the pressure on the downstream side (boom load pressure P_{a1}). This can compensate change in the passing flow rate of the boom meter-in valve 8a1 due to the influence of the differential pressure. The current command $I_{a1,ref}$ to the solenoid proportional pressure reducing valves 8a2 for the boom directional control valve is computed by using expressions (2), (4), and (5).

The arm cylinder meter-in opening control section 10e2 uses the target flow rate Q_{a2} , the estimated flow rate Q_{e2} , the pump delivery pressure P_d and the arm load pressure P_{a2} to compute the current command $I_{a2,ref}$ from expressions (2), (4), and (5). The bucket cylinder meter-in opening control section 10e3 uses the target flow rate Q_{a3} , the estimated flow rate Q_{e3} , the pump delivery pressure P_d and the bucket load pressure P_{a3} to compute the current command $I_{a3,ref}$ from expressions (2), (4), and (5).

The construction machine 100 according to the present embodiment further includes the first pressure sensor 51 disposed on the respective hydraulic fluid lines that couple the hydraulic pump 7 to the plural directional control valves 8a1, 8a3, and 8a5 and the second pressure sensors 52 to 57 disposed on the respective hydraulic fluid lines that couple the plural directional control valves 8a1, 8a3, and 8a5 to the plural hydraulic actuators 4a, 5a, and 6a. The controller 10 controls the plural directional control valves 8a1, 8a3, and 8a5 according to the differential pressures across the plural directional control valves 8a1, 8a3, and 8a5 sensed by the first pressure sensor 51 and the second pressure sensors 52 to 57.

According to the present embodiment configured as above, the following effect is obtained in addition to the same effects as the first embodiment.

By deciding the target opening amount A_{a1} of the meter-in valves 8a1, 8a3, and 8a5 in consideration of the differential pressure between the pressure on the upstream side of the meter-in valves 8a1, 8a3, and 8a5 (pump delivery pressure P_d) and the pressure on the downstream side (load pressure P_{a1}), change in the passing flow rate of the meter-in valve due to the influence of the differential pressure can be compensated. This can improve the velocity responsiveness of the hydraulic actuators 4a to 6a with respect to variation in the load pressure.

Fifth Embodiment

A hydraulic excavator according to a fifth embodiment of the present invention will be described with focus on a difference from the fourth embodiment.

FIG. 14 is a control block diagram that represents details of a calculation function of the bleed-off opening control section 10f according to the fifth embodiment.

The bleed-off opening control section 10f computes the current command $I_{b,ref}$ to the solenoid proportional pressure reducing valve 8b2 for the bleed-off valve on the basis of the pump delivery pressure P_d inputted from the pump delivery pressure sensor 51 in addition to the determination flag inputted from the combined operation determining section 10b.

When a load is applied to the hydraulic actuator, the pump delivery pressure P_d increases and the discharge flow rate of discharge from the bleed-off valve 8b1 to the tank 41 increases. It is anticipated that, when the discharge flow rate increases, the flow rate of inflow to the hydraulic actuator decreases and the error between the target flow rate and the estimated flow rate increases.

In order to prevent the increase in the flow rate error when a load is applied to the hydraulic actuator, for example, the constant opening A_{const} shown in FIG. 14 is computed from the following expression (6) according to the pump delivery pressure P_d .

[Expression 6]

$$A_{const} = k \frac{Q_{b,const}}{\sqrt{P_d}} \quad (6)$$

Here, $Q_{b,const}$ is a target constant discharge flow rate of discharge from the bleed-off valve 8b1. The pump delivery pressure P_d sensed by the pump delivery pressure sensor 51 is used as input and the constant opening A_{const} is computed by TBL3 to carry out calculation of expression (6).

By TBL3, the opening amount of the bleed-off valve 8b1 is adjusted to carry out discharge at the constant flow rate $Q_{b,const}$ irrespective of variation in the pump delivery pressure P_d .

The construction machine according to the present embodiment further includes the pressure sensor 51 disposed downstream of the hydraulic pump 7 and the controller 10 corrects the opening amount of the bleed-off valve 8b1 according to the pressure on the downstream side of the hydraulic pump 7 sensed by the pressure sensor 51.

According to the present embodiment configured as above, the following effect is obtained in addition to the same effects as the fourth embodiment.

By carrying out control in such a direction that the opening of the bleed-off valve 8b1 is closed in response to increase in the load on the hydraulic actuators 4a, 5a, and 6a and reducing the discharge flow rate to the tank 41, decrease in the flow rate of inflow to the hydraulic actuators 4a, 5a, and 6a can be prevented.

A hydraulic excavator according to a sixth embodiment of the present invention will be described with focus on a difference from the first embodiment.

FIG. 15 is a diagram schematically illustrating a hydraulic actuator control system according to the sixth embodiment.

In the hydraulic actuator control system illustrated in FIG. 15, a boom pressure compensating valve 61 is installed upstream of the boom directional control valve 8a1, an arm pressure compensating valve 62 is installed upstream of the arm directional control valve 8a3, and a bucket pressure compensating valve 63 is installed upstream of the bucket directional control valve 8a5. The pressure compensating valves 61 to 63 have pressure receiving parts to which the pressures in hydraulic fluid lines between the pressure compensating valves 61 to 63 and the directional control valves 8a1, 8a3, and 8a5 and the pressures in hydraulic fluid lines between the directional control valves 8a1, 8a3, and 8a5 and the hydraulic actuators 4a, 5a, and 6a are introduced, and adjust the openings in such a manner that the pressures on the upstream side and the downstream side of the directional control valves 8a1, 8a3, and 8a5 are kept constant.

The construction machine 100 according to the present embodiment includes each of the pressure compensating valves 61 to 63 for keeping the pressure difference between the upstream side and the downstream side of the plural directional control valves 8a1, 8a3, and 8a5 constant on the respective upstream sides of the plural directional control valves 8a1, 8a3, and 8a5.

According to the present embodiment configured as above, the following effect is obtained in addition to the same effects as the first embodiment.

The pressure compensating valves 61 to 63 cause the differential pressures across the meter-in valves 8a1, 8a3, and 8a5 to be adjusted to be constant. Due to this, without installing the pressure sensors 51 to 57 illustrated in FIG. 12, change in the passing flow rate of the meter-in valves due to the influence of the differential pressures across the meter-in valves 8a1, 8a3, and 8a5 can be compensated. This can suppress the installation cost of the pressure sensor and simplify the electronic control logic of the controller 10.

Although the embodiments of the present invention have been described in detail above, the present invention is not limited to the above-described embodiments and various modification examples are included therein. For example, the above-described embodiments are what are described in detail for explaining the present invention in an easy-to-understand manner and are not necessarily limited to what include all configurations described. Furthermore, it is also possible to add part of a configuration of a certain embodiment to a configuration of another embodiment, and it is also possible to delete part of a configuration of a certain embodiment or replace the part by part of another embodiment.

The invention claimed is:

1. A construction machine comprising:
a hydraulic pump;
a regulator that adjusts a delivery flow rate of the hydraulic pump;
a plurality of hydraulic actuators;

19

a plurality of directional control valves that adjust a flow rate of a hydraulic fluid that is delivered from the hydraulic pump and is distributed to the plurality of hydraulic actuators; an operation device for operating the plurality of hydraulic actuators; and a controller configured to decide a target flow rate that is a target value of an inflow flow rate of each of the plurality of hydraulic actuators on a basis of an operation signal inputted from the operation device and control the regulator and the plurality of directional control valves according to the respective target flow rates of the plurality of hydraulic actuators, wherein the construction machine includes velocity sensors that sense respective operation velocities of the plurality of hydraulic actuators, and the controller is configured to calculate the respective inflow flow rates of the plurality of hydraulic actuators on a basis of the respective operation velocities of the plurality of hydraulic actuators sensed by the velocity sensors, determine whether or not combined operation in which two or more hydraulic actuators in the plurality of hydraulic actuators are simultaneously operated is being carried out, on a basis of the operation signal inputted from the operation device, and in a case of determining that the combined operation is being carried out, control the regulator in such a manner that the delivery flow rate of the hydraulic pump becomes larger than a total target flow rate of the plurality of hydraulic actuators and control respective opening amounts of the plurality of directional control valves in such a manner that a difference between the respective target flow rates of the plurality of hydraulic actuators and the respective inflow flow rates of the plurality of hydraulic actuators sensed by the velocity sensors becomes small.

2. The construction machine according to claim 1, wherein the construction machine includes a bleed-off valve for discharging a surplus part of the hydraulic fluid delivered by the hydraulic pump, in such a manner that the bleed-off valve is driven independently of the plurality of directional control valves, and the controller is configured to carry out control to open the bleed-off valve in the case of determining that the combined operation is being carried out and close the bleed-off valve in a case of determining that the combined operation is not being carried out.

3. The construction machine according to claim 2, wherein

the construction machine further includes a pressure sensor disposed downstream of the hydraulic pump, and the controller is configured to correct an opening amount of the bleed-off valve according to a pressure of a downstream side of the hydraulic pump sensed by the pressure sensor.

4. The construction machine according to claim 1, wherein

the construction machine includes a first pressure sensor disposed on respective hydraulic fluid lines that couple the hydraulic pump to the plurality of directional control valves, and

20

second pressure sensors disposed on respective hydraulic fluid lines that couple the plurality of directional control valves to the plurality of hydraulic actuators, and the controller is configured to control the plurality of directional control valves according to differential pressures across the plurality of directional control valves sensed by the first pressure sensor and the second pressure sensors.

5. The construction machine according to claim 1, wherein

the construction machine includes a pressure compensating valve for keeping pressure difference between an upstream side and a downstream side of each of the plurality of directional control valves constant, the pressure compensating valve being provided on each of the upstream sides of the plurality of directional control valves.

6. A construction machine comprising:

a hydraulic pump;
a regulator that adjusts a delivery flow rate of the hydraulic pump;
a plurality of hydraulic actuators;
a plurality of directional control valves that adjust a flow rate of hydraulic fluid that is delivered from the hydraulic pump and is distributed to the plurality of hydraulic actuators;

an operation device for operating the plurality of hydraulic actuators; and

a controller configured to decide a target flow rate that is a target value of an inflow flow rate of each of the plurality of hydraulic actuators on a basis of an operation signal inputted from the operation device and control the regulator and the plurality of directional control valves according to the respective target flow rates of the plurality of hydraulic actuators, wherein the construction machine includes a plurality of flow rate sensors each disposed upstream of the plurality of directional control valves that sense respective operation velocities of the plurality of hydraulic actuators, and

the controller is configured to calculate the respective inflow flow rates of the plurality of hydraulic actuators on a basis of the respective operation velocities of the plurality of hydraulic actuators sensed by the flow rate sensors,

determine whether or not combined operation in which two or more hydraulic actuators in the plurality of hydraulic actuators are simultaneously operated is being carried out, on a basis of the operation signal inputted from the operation device,

in a case of determining that the combined operation is being carried out, control the regulator in such a manner that the delivery flow rate of the hydraulic pump becomes larger than a total target flow rate of the plurality of hydraulic actuators and control respective opening amounts of the plurality of directional control valves in such a manner that a difference between the respective target flow rates of the plurality of hydraulic actuators and the respective inflow flow rates of the plurality of hydraulic actuators sensed by the flow rate sensors becomes small.
